WILLIAM A. BERNARD, OF NEW HAVEN, CONNECTICUT, ASSIGNOR TO THE WILLIAM SCHOLIHORN COMPANY, OF NEW HAVEN, CONNECTICUT, A CORPORATION OF CONNECTICUT.

HAND-TOOL.

1,159,641.

Specification of Letters Patent.

Patented Nov. 9, 1915.

Application filed May 26, 1915. Serial No. 30,598.

To all whom it may concern:

Be it known that I, WILLIAM A. BERNARD, a citizen of the United States, residing in New Haven, in the county of New Haven 5 and State of Connecticut, have invented certain new and useful Improvements in Hand-Tools, of which the following is a full, clear, and exact description.

This invention relates to hand tools and 10 more particularly to those where a very powerful leverage is required. I have shown my improvements as applied to a bolt cutter, but they may be used to advantage in tools of other types.

15 The primary objects of the invention are to provide simple, effective means affording a powerful leverage; to furnish improved means for supporting and centering operating handles or lever members which are 20 pivoted non-coincidently; and to improve the general construction and operation of devices of the class to which the invention relates.

To these and other ends, the invention 25 consists in the novel features and combinations of parts to be hereinafter described and claimed.

In the accompanying drawing, Figure 1 is a front view of a bolt cutter embodying 30 my improvements, with the jaws open; Fig. 2 is an enlarged fragmentary view of the bolt cutter, taken from the rear, and showing the cutting jaws in contact with each other; Fig. 3 is an edge view of Fig. 2; and 35 Fig. 4 is a section on line 4—4 of Fig. 2.

The bolt cutter shown in the drawing comprises a pair of levers 5, 6 pivoted together intermediate of their ends by means of a pivot bolt 7. In front of the pivot 7, the 40 levers are provided with cutting jaws 5^a, 6^a respectively. The portions of the levers 5, 6 which are disposed rearwardly of the pivot are of greater length than the cutting jaws and form elongated shanks 5^b, 6^b which 45 when moved away from each other bring the cutting jaws together. The rear extremities of the levers 5, 6 are adapted to be moved toward and away from each other by means of operating levers 8, 9 which are preferably 50 constructed from sheet metal bent into U-shaped cross-section. The forward end portions of the operating handles are forked or bifurcated so as to straddle the respective shanks 5^b, 6^b to which they are pivoted by 55 means of pivot bolts 10, 11 respectively. At the rear of the pivot bolts 10, 11, the operating levers are pivoted to a supporting member or block 12 by means of pivot bolts 13, 14 respectively. This block 12 is straddled by the forked forward end portions of the operating levers, and the latter are pivoted to the block on opposite sides respectively of the center of the block. In other words, the pivots of the respective operating levers on the supporting means are non-coincident, 60 being spaced on opposite sides respectively of the lengthwise axis of the tool as a whole, as shown, the distance between the pivots 13, 14 and the pivots 10, 11 respectively being quite short as compared to the length of the 65 operating levers. It will be apparent that by the construction described, a very powerful compound leverage is obtained so that large bolts may be cut off by the jaws 5^a, 6^a by the expenditure of comparatively little 70 effort.

In order to maintain the two sets of levers in a symmetrical relation in respect to the lengthwise axis of the tool, or, in other words, to prevent the supporting block 12 75 from taking an inclined position with respect to the lengthwise axis of the tool, suitable means are provided for maintaining the imaginary line between the pivots 13, 14 perpendicular to a line bisecting the angle 80 between the working levers 5, 6 and the angle between the operating levers 8, 9. In the form shown, the block 12 is held perpendicular to the line bisecting the angle 85 between the members 5, 6 by means of a 90 centering device disposed between the shank portions 5^b, 6^b. This centering device comprises a tubular member 15 attached to the block 12, and serving as a mounting for a sliding member 16, which engages both of 95 the levers 5, 6. The member 16 may be in the form of a small cylinder engaging inclined surfaces 5^c, 6^c on the inner edges of the levers 5, 6 immediately at the rear of the pivot 7. Said member 16 is supported on a 100 rod 17 entering and guided in the tubular member 15, and yieldingly cushioned by a spring 18 interposed between the bottom of the socket in the member 15, and the inner end of the rod 17, as shown in Fig. 4. The 105 spring 18 is normally held under compression so as to force the member 16 into tight engagement with the inclined surfaces 5^c, 6^c respectively.

In cutting a bolt or the like, the tool is 110

first opened into the position shown in Fig. 1. Then when the jaws 5^a, 6^a have been engaged with the bolt shank, the levers 8, 9 are pulled toward each other, and the cutting edges are brought together on the bolt 5 by the separation of the rear extremities of the levers 5, 6 through their connection with the forward extremities of the respective operating levers by means of the pivots 10, 11, as will be obvious. As will be noted 10 from Fig. 1, the pivots 10, 11 are well in advance of the pivots 13, 14 when the tool is in the open position, but when the jaws 5^a, 6^a are brought to the closed position, as 15 shown in Fig. 2, the pivots 13, 14 are brought almost into transverse alinement with the pivots 11, 10, so that at this time the movement of the cutting jaws is extremely slight as compared to that of the 20 rear extremities of the operating levers, whereby a very powerful action is obtained. As the jaws are closed together, the member 15 carried by the block 12 is thrust forward relative to the levers 5, 6 and the pivot 7, 25 as will be obvious, and it carries forward the member 16 which continues to engage the inclined surfaces 5^e, 6^e and thereby exerts a kind of wedging action on the members 5, 6, tending to close the jaws. The 30 main function of the device 15, 16, however, is to center the block 12, as previously described, and this is done by keeping the member 15 in the line bisecting the angle between the levers. The spring 18 cushions 35 the lever engaging device 16, and, by allowing relative movement between it and its supporting part, permits the co-operating parts 5^e, 6^e of the levers to be cut along straight lines without disturbing the easy, 40 noiseless working of the tool.

In order to limit the closing movement of the jaws, the block 12 may be provided with a suitable stop. In the form shown, the centering member 15 is connected with the block 45 by a threaded shank 15^a extending through the block to the rear thereof, and a stop block 19 is threaded on the rearwardly extending portion of the shank 15^a. The stop block 19 is adapted to engage the inner edges of the operating handles, as shown in Fig. 2, and thereby arrest them in the desired position. The stop may be fixed in any of a number of different positions along the shank or stem 15^a by means of a set screw 50, the inner end of which acts on a small piece 21 of copper or other soft metal which engages the threads of the stem without mutilating the same.

Various changes in the details of the device 60 may be adopted without departing from the scope of the invention as defined in the claims.

What I claim is:—

1. In a hand tool the combination of a 65 pair of working levers, a pivot member piv-

oting said levers together intermediate of their ends, a pair of operating levers having forked forward ends embracing the rear extremities of said working levers and pivoted thereto, a block interposed between said operating levers rearwardly of the pivotal connections of the latter with said working levers, and extending at one side into the forked portion of one lever and at the other side into the forked portion of the other 75 lever, and means for pivoting said operating levers to said block on opposite sides respectively of the longitudinal axis of the tool, substantially as described.

2. In a hand tool, the combination of a 80 pair of working levers, a pair of operating levers having forked forward ends pivoted to the rear extremities of the respective working levers, a block set in between the forward end portions of said operating levers and entering the respective forked portions thereof, means for pivoting said operating levers to said block, and a centering device carried by the block and extending 85 between and into engagement with said working levers; substantially as described.

3. In a hand tool, the combination of a 90 pair of working levers, a pair of operating levers therefor, and a yielding wedge device 95 located between the working levers and actuated by said operating levers; substantially as described.

4. In a hand tool, the combination of a 100 pair of working levers, a pair of operating levers therefor, a pivotal support for said operating levers, and a centering device for the tool comprising two telescoping parts having a yielding relation to each other, one of said parts mounted on said pivotal support, and the other of said parts engaging 105 the working levers so as to wedge them apart; substantially as described.

5. In a hand tool, the combination of a 110 pair of working levers, means for pivoting said levers together intermediate of their ends, a pair of operating levers pivoted at their forward ends to the respective rear extremities of the working levers, a block interposed between said operating levers, devices for pivoting said operating levers to said block on opposite sides of the longitudinal axis of the tool, and a centering device projecting forwardly from said block into the space between the shanks of said working levers and having a wedge-like engagement with said working levers at the rear of their pivot; substantially as described.

6. In a hand tool, the combination of a 125 pair of working levers, a pair of operating levers, means for pivoting the forward ends of the operating levers to the respective rear extremities of the working levers, a block interposed between the operating levers, devices for pivoting said operating levers to 130

said block on opposite sides respectively of the longitudinal axis of the tool, a support projecting rearwardly from said block between said operating levers, and a stop for 5 said operating levers adjustably mounted on said support; substantially as described.

7. In a hand tool, the combination of a pair of levers, working means operated thereby, a block forming a pivotal support 10 for said levers, and a stop adjustably mounted on said block and interposed between said levers; substantially as described.

8. In a hand tool, the combination of a pair of working levers, a pair of operating 15 levers, a block to which the operating levers are pivoted, a centering device projecting

from the block on one side and a stop projecting from the block on the opposite side; substantially as described.

9. In a hand tool, the combination of a 20 pair of working levers pivoted together intermediate their ends, a pair of operating levers, a block to which the operating levers are pivoted, and a centering device comprising a part secured to and projecting from 25 the block and a second part telescoping with the first and yieldingly held in engagement with said working levers at the rear of their pivot; substantially as described.

In witness whereof, I have hereunto set 30 my hand on the 25th day of May, 1915.

WILLIAM A. BERNARD.
